DESIGN.

C. T. GROSJEAN.

KNIFE BLADE.

No. 15,676.

Patented Dec. 30, 1884.

UNITED STATES PATENT OFFICE.

CHARLES T. GROSJEAN, OF NEW YORK, N. Y., ASSIGNOR TO TIFFANY & CO.,
OF SAME PLACE.

DESIGN FOR A KNIFE-BLADE.

SPECIFICATION forming part of Design No. 15,676, dated December 30, 1884.

Application filed October 11, 1884. Term of patent 14 years.

To all whom it may concern:

Be it known that I, CHARLES T. GROSJEAN, a citizen of the United States, residing in the city, county, and State of New York, have invented and produced a new and original Design for Blades of Table-Knives, of which the following is a specification, reference being had to the accompanying drawings, forming part thereof.

The design of this blade consists in the configuration of its back and front edges. Such configuration is composed of a swell or rise in the back edge, commencing at the tang, extending about one-third of the length of such back edge. Then there is a depression, about one-third of the length, at the center of the back edge. The back edge is then curved upward and left rounding toward the end of the blade. The front edge is just the reverse from the tang out, there being a recessing of the edge at points opposite the swell or rise in the back, a swell at center of front edge opposite the depression on the back, and a curving upward toward the end of the blade to conform to the curve on the back near the end.

In the drawings, Figure 1 is a dessert-knife. Fig. 2 is a breakfast-knife. Fig. 3 is a dinner-knife.

a is the tang. *b* is the blade. *c* is the swell or rise, commencing on the back edge from the tang *a* and extending about one-third of the distance along the edge. *d* is a depression extending from such swell for about another third of the distance along the back edge. Then there commences an upward curving, *e*, of the back edge, which rounds itself off toward the point or end of the blade. *f* is a slight recessing of the front edge of the blade, commencing at the tang *a* and extending along the said edge about one third of the distance, exactly conforming as a depression to the swell or rise of the back edge and immediately opposite it. *g* is a swell at the center portion of the front edge of the blade, conforming as a swell to the depression *d* on the back edge and extending along about the same distance. The front edge then assumes another swell or rise—that is, curves or rises upward at *h* to the point or end of the blade—thereby conforming to the curve *e* on the back.

I claim—

The design for a knife-blade, having the shape or outline shown and described.

CHAS. T. GROSJEAN.
